(57) **CLAIM**

The ornamental design for a paper towel holder, as shown and described.

DESCRIPTION

FIG. 1 is a perspective view of the paper towel holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2 thereof;

FIG. 10 is a perspective view thereof, showing the paper towel holder in a first state of use;

FIG. 11 is a perspective view thereof, showing the paper towel holder in a second state of use; and,

FIG. 12 is a perspective view thereof, showing the paper towel holder in a third state of use.

Broken lines are used to illustrate portions of the paper towel holder. Other broken lines illustrate environmental subject matter that form no part of the claimed design.

The dash dot dash lines in FIGS. 2 and 9 are for the purpose of depicting the boundary lines of the enlarged view and form no part of the claimed design.
